UNITED STATES PATENT OFFICE

HUGO R. SWANSON, OF BROOKLYN, NEW YORK, ASSIGNOR TO TRIANGLE KAPOK MANUFACTURE CORPORATION, OF NEW YORK, N. Y., A CORPORATION OF DELAWARE

CLEANING MACHINE

Application filed April 13, 1928. Serial No. 269,668.

One of the objects of this invention is the provision of a cleaning machine for removing dust and dirt from various articles such as pillows, mattresses and the like.

- 5 A still further object of this invention is the provision of a relatively simple device for efficiently and rapidly removing dust and other loose particles from pillows, mattresses and similar objects.
- 10 A still further object of this invention is the provision of a cleaning machine for removing dust and loose particles from pillows and mattresses without permitting the dust which is removed to escape into the atmosphere so as to jeopardize the health of the workmen.

20 A still further object of this invention is the provision of a cleaning machine having a circulatory system for air and means for removing the dust and other loose particles from the objects to be cleaned in a manner to permit the dust to be taken up by the circulating air.

25 These and other objects as will appear from the following disclosure are secured by means of this invention.

This invention resides substantially in the combination, construction, arrangement and relative location of parts, all as will more 30 fully appear from the following disclosure.

Referring to the drawings: Figure 1 is a front elevational view of the device showing the complete association of the elements.

Fig. 2 is a side elevational view of the 35 device of Fig. 1 showing a portion in cross section on the line 2--2 of Fig. 1.

Fig. 3 is a front elevational view of a modified form of the device which does not employ revolving brushes, and

40 Fig. 4 is a side elevational view of the arrangement of Fig. 3.

In the process of removing dust and other loose particles from objects to be cleaned, it is well known that there is a tendency for 45 the dust and other light particles which are agitated in their removal from the object to float in the air to the injury of the workmen cleaning the object.

The machine of the invention removes 50 dust from the room but does not exhaust the

air in the room, consequently the oxygen in the room is not exhausted and the temperature of the room is not affected.

It is the general purpose of the invention to provide a device which will rapidly and 55 efficiently clean objects such as pillows and mattresses, while, at the same time, preventing the removed particles of dust from floating in the air where they will cause injury by contaminating the air which the workmen breathe.

Referring to the drawings wherein two forms of the invention have been disclosed for the purpose of illustrating the principles of this invention, there is shown at Fig. 1, 60 a platform 1 of any suitable type which may be the top of a table for instance, supported by means of the legs 2. The table is provided with a hood having two sides and a back united by a curved top to provide an 65 opening therein at the front of the platform through which the object to be cleaned may be inserted. The rear wall of the hood is provided with a rectangular opening 4 extending substantially throughout the width 70 thereof. A plurality of revolving brushes are shown at 5 and 6. These brushes are mounted on a shaft 7 which is journaled under the platform and the brushes are so arranged as to project a short distance 75 through openings in the platform. The shaft 7 is driven by means of a pulley 8 from any suitable power source. A conduit comprising two branches 9 and 10 is arranged so as to enclose the brushes 5 and 6 80 and converge into a single conduit 11 which is connected through the conduit 12 with a dust house 13.

Within the dust house is a porous fabric bag 14 which is completely closed and is in 85 communication at one end with a conduit 15 leading to a blower 16. A conduit 17 extends from the blower to a pyramidal shaped hood 18 which fits over the opening 4 on the hood 3 so that the air passing 90 through the opening 4 is received within the hood 18. It is pointed out the branches 9 and 10 are curved to correspond with the brush curvature so that the air is guided substantially peripherally around the brushes 95 100

5 and 6 and is delivered from the top of the brush in a substantially tangential direction as illustrated by the arrows. Viewing the brushes from the end shown in Fig. 2 they 5 rotate in a clockwise direction. The conduit 17 connects to the suction end of the blower 16 and the conduit 15 connects to the delivery end.

In the use of this device the brushes are 10 revolved at the proper rate and the blower 16 is driven by any suitable means to cause the desired flow of air. The object to be cleaned as for instance a pillow is placed on the platform 1 so that the brushes 5 and 6 15 are in contact therewith. The pillow can be moved back and forth so that the entire surface encounters the rapidly revolving brushes. The brushes remove the particles of dust and the like from the surface of the 20 pillows which particles are taken up by the current of air flowing from branches 9 and 10 and are delivered in the direction of the arrows and are carried through the opening 4 into the hood 18 and conduit 17 by the air 25 flowing to the suction side of the blower 16. The dust laden air is delivered into conduit 15 and thence to the dust bag in the dust house. The dust bag acts as a screen or filter removing the particles of dust from the 30 air as it flows through the dust bag. The cleaned air then delivers from the dust house through the conduits 12 and 11 and then is delivered through the branches 9 and 10 to the brushes as before.

35 The air continuously circulating as described takes up the particles removed from the pillows by the brushes and carries them to the dust bag where the air is purged. The rapidly moving air also tends to remove 40 some of the particles from the pillows in conjunction with the beating and scouring action of the brushes. One of the important features of this form of the construction is the fact that the air is guided around the 45 revolving brushes and travels in the same direction as the periphery of the revolving brushes. As a result of this arrangement the dust is rapidly and efficiently removed from the pillows and taken to the dust house 50 without permitting any of it to escape into the surrounding atmosphere.

In the form shown in Figs. 3 and 4 the platform supported by the legs 2 and in turn supporting the hood 3 are the same as 55 in the previous construction. Each side wall of the hood 3 is provided with openings as shown at 20 and 21. The opening 20 is connected by the conduit 22 to the suction side of the blower 23. The delivery side of the 60 blower is connected through the conduit 24 which delivers into a dust bag (not shown but similar to bag 14, Fig. 1) within the dust house 25. The purged air after passing through the dust bag is delivered 65 through conduit 26 to the opening 21. In

this form of construction the current of air travels transversely of the hood 3 and the object to be cleaned such as the mattress is placed on platform 1. The dust is loosened and removed from the mattress by beating it and is taken up by the transverse current of air which carries it to the dust bag 30. The cleaned air is then carried through conduit 26 to hood 3 where it may again become dust laden. In this form of device it 70 has also been found that the object can be cleaned without the escape of dust into the surrounding atmosphere. 75

I am well aware that numerous changes in the details of construction and relative association of parts will readily occur to those skilled in the art without departing from the principles of this invention and I do not therefore desire to be limited to the constructions shown for purposes of illustration, but rather to the scope of my invention as it is defined in the appended claims. 80

Having now disclosed the principles of my invention, what I seek to secure by United States Letters Patent is: 90

1. In a device of the type described, the combination of a platform having an opening therein, a brush in registry with said opening, a hood over said platform having a discharge opening, a conduit system connected to the platform opening, and to the hood discharge opening, means for creating a continuous current of air in said system, and means for removing dust from the air leaving said discharge opening. 100

2. In a device of the type described, the combination with a platform, an open ended hood support on said platform having an aperture in one wall thereof and means on said platform for loosening and removing the dust from the article to be cleaned of a circulatory system opening at one end into the aperture in the hood and opening at the other end adjacent said means, means in said system for creating a current of air and means also in said system for removing the dust from the current of air. 105

3. In a device of the type described, means for supporting an object to be cleaned, means for removing dust therefrom, means for creating a continuous current of air in the form of a substantially closed circuit, means for guiding said current past said removing means to carry the dust in a substantially confined path, and means in the path of said current for collecting the dust without interfering with the substantial continuity of said current. 115

4. In a cleaning machine the combination with a platform, an open ended hood supported on said platform and a plurality of revolving brushes supported below said platform and projecting therethrough of a conduit system opening at one end into said hood and opening at the other end through 120 125 130

the openings in said platform, means in said conduit system for creating a current of air and means in said system for purging the air of dust and the like.

5 5. In a cleaning machine the combination with a chamber and brush means extending through said supporting means and into said chamber having means for supporting an object to be cleaned for removing the dust from the objects of means connected to said chamber comprising a conduit system for removing the dust from said chamber, means in said conduit system for creating a current of air therein, means for purging the air of dust and means for returning the purged air to said chamber.

10 6. In a cleaning machine the combination with an open ended chamber of means for supporting an object to be cleaned, means for removing dust therefrom consisting in a plurality of revolving brushes extending through said supporting means, of a conduit system connected at one end to said chamber, a blower in said conduit system, means in said conduit system for removing dust from the air therein and means for guiding the cleaned air substantially peripherally around said revolving brushes.

15 7. In a cleaning machine the combination of means for supporting an object to be cleaned, brush means, for removing dust and the like from such objects, extending through said supporting means, and means comprising guiding means for the supply and withdrawal of air in a continuous circuit past the brush means, for confining the dust laden air to a limited path, means for moving air through the guiding means and means for removing the dust from the moving air.

20 40. In testimony whereof I have hereunto set my hand on this 10th day of April, A. D., 1928.

HUGO R. SWANSON.
